UNITED STATES PATENT OFFICE.

ROBERT TOAL, OF ST. LOUIS, MISSOURI, ASSIGNOR TO THE MENGEL COMPANY, OF LOUISVILLE, KENTUCKY, A CORPORATION OF NEW JERSEY.

CHILD'S ROCKER.

1,412,723.

Specification of Letters Patent. Patented Apr. 11, 1922.

Application filed October 28, 1921. Serial No. 511,055.

To all whom it may concern:

Be it known that I, ROBERT TOAL, a citizen of the United States, residing at St. Louis, State of Missouri, have invented certain new and useful Improvements in Children's Rockers, of which the following is a specification.

This invention pertains to rockers, designed more particularly for the use of children, and has for its main object the production of a device which is simple and safe and cheap of manufacture.

A further object of the invention is the production of a structure wherein a tandem arrangement is present, whereby two children may occupy the rocker at one and the same time and either one or both take part in the actuation of the structure to cause it to rock.

20 The invention is illustrated in the accompanying drawings, wherein,

Fig. 1 is a perspective view of the rocker; Fig. 2 a longitudinal sectional view;

Fig. 3 a transverse vertical sectional view taken on the line III—III of Fig. 2;

Fig. 4 a like view taken on the line IV—IV of Fig. 2; and

Fig. 5 a vertical longitudinal sectional view of a modified form of a single seated rocker.

Referring to Figs. 1 to 4 inclusive, the main supporting frame may be said to comprise two longitudinally disposed bars 1 and 2 upon which are imposed the seats 3 and 4, said seats being held in position upon the bars or rails 1 and 2 by bolts 5 provided with wing nuts 6. As will be seen upon reference to Fig. 2 the side rails or bars are provided with a plurality of openings 7 so

40 that the seats may be adjusted longitudinally of the bars and thus be brought closer together or separated, as may be desired. Journaled between the side bars or rails, at the ends thereof, are cross bars or rods 8

45 and 9, and secured to each of said rods are arms 10 and 11, each arm in turn having secured thereto a rocker 12. A cross bar 13 is secured in the lower end of the oppositely disposed arms 10 and 11, which bar 13 serves 50 to space the rockers apart and to hold them in their proper relation to each other. To maintain the arms, and consequently the rockers in their proper relation to each other in pairs, there is provided a platform com-

posed of two longitudinally disposed rails 14 and 15 connected to each other by a foot board 16. The rails 14 and 15 are notched adjacent each end and pass down over the cross bars 13, thus insuring uniform movement of the oppositely disposed pair of rockers. The bars 14 and 15 are also notched at their mid-length to receive a cross bar 17, said cross bar being secured in the lower ends of two levers 18 and 19, the latter being fulcrumed upon a cross rod 20 secured in the 65 side rails 1 and 2. Said levers at their upper ends carry a handle 21 which may be grasped by the occupant or occupants of the rocker and by pulling and pushing upon the same, thereby cause the rocker to function. Motion may also be imparted to the rocker by a child occupying the seat, the child placing its feet upon the foot board 16 and exerting a pushing motion thereon.

The rockers, as will be noted upon reference to the drawings, more particularly Fig. 4, stand in vertical alinement with the side rails 1 and 2 and consequently the ends thereof act as limiting stops to prevent the rocker from being swung too far. It is to 80 be noted that in this construction no cross bar or the like is necessary to limit the movement, a feature commonly employed in swings or rockers of this same general type. It will also be noted that by the employment of cotter pins for connecting the lever frame composed of the levers 18 and 19, the cross bar 17 and the handle 21, the structure may be readily disassembled for the purpose of shipment, the seats likewise being readily 85 removable, as well as the rods 8 and 9 from the side rails in which their ends find their bearing.

In Fig. 5 a modification of the invention is illustrated wherein but a single seat is 95 present. The seat, denoted by 30, is secured to the longitudinally disposed bars, only one of which, 1, is shown. The rear rockers 12, as in the former construction, are secured to arms, as 10 and 11, pivotally mounted at 100 their upper ends upon the cross rod 8. The cross bar 13 is also present, attaching the rockers to each other. The forward pair of rockers, denoted in this instance by 12^a (and only one of which is shown) are secured to 105 a pair of levers 31 which extend upwardly between the longitudinally disposed bars, being fulcrumed upon a cross rod 8^a. A

cross bar or handle 32 connects said levers adjacent their upper ends and a trough or shelf 33 is pendulously supported from said bar 32 by a pair of hangers or plates 34 arranged at the ends of the shelf. Instead of employing a pair of supporting rails, as 14 and 15, a platform 35 of a length sufficient to span the cross bars 13, is present under this construction. A pair of cleats 36 are 10 secured to the under face of the platform adjacent each end thereof, said cleats embracing the cross bars and thus causing the rockers to move in unison. Turn-buckles 37 will be secured to the cleats so that when 15 moved to the position shown in Fig. 6 they will prevent the platform 35 from being raised free of engagement with the cross bars 13. The levers 31 are, in a sense, the equivalent of the upright levers 18 and 19 20 in the construction shown in Fig. 1, with the forward pair of rockers secured to the lower ends of said levers 18 and 19. In other words, the structure is substantially identical with that shown in Fig. 1 except 25 that it is shortened up one half and the rockers secured to the levers 18 and 19 instead of to a pair of levers or arms 10 and 11, as in Fig. 1.

What is claimed is,—

- 30 1. In a rocker, the combination of a main supporting frame carrying oppositely disposed seats located at its ends; a pair of rockers fulcrumed upon the frame at each end thereof; an exposed foot platform 35 interconnected with said rockers and causing the same to rock in unison; and an actuating lever extending upwardly between the seats, said lever being fulcrumed upon the supporting frame intermediate the seats and attached to the platform for causing a relative movement between said platform and the

frame and a consequent rocking of the structure.

2. In a rocker, the combination of a supporting frame comprising two longitudinally disposed side bars; a seat secured to said bars at each end thereof; a cross bar journaled in the side bars adjacent the ends thereof; a pair of rockers located beneath each of said bars, arms extending upwardly 45 from said rockers and connected to said bars; a bar extending across between each pair of rockers securing the same in spaced relation; a platform comprising two longitudinally disposed cross bars, the same being notched to engage the cross bars aforesaid, and a foot-board secured to said cross bars; a pair of levers fulcrumed to the side rails of the main supporting frame at substantially their midlength; a bar attached to the lower ends of said levers, said bar passing through notches formed in the longitudinally disposed rails of the platform; and a handle secured to the upper end of the levers. 50

3. In a rocker, the combination of a main supporting frame comprising two longitudinally disposed bars or rails, a seat secured thereon; a pair of ground contacting rockers located adjacent each end of the frame; 55 means for supporting said rockers in pivotal relation to the frame, said rockers being located beneath the side rails and adapted to contact the rails to limit the rocking movement of the structure; and an exposed foot platform connected to the rockers and serving to hold the same in proper spaced relation. 75

In testimony whereof I have signed my name to this specification.

ROBERT TOAL.
